UNITED STATES PATENT OFFICE.

EDWARD E. HAMILTON, OF NORTHBORO, MASSACHUSETTS.

HINGE MEMBER FOR BARRETTES AND THE LIKE.

1,243,834.

Specification of Letters Patent. Patented Oct. 23, 1917.

Application filed March 26, 1917. Serial No. 157,374.

To all whom it may concern:

Be it known that I, EDWARD E. HAMILTON, a citizen of the United States, residing at Northboro, in the county of Worcester and 5 State of Massachusetts, have invented a new and useful Hinge Member for Barrettes and the like, of which the following is a specification.

This invention relates to a hinge member 10 for barrettes and similar articles.

The principal objects of the invention are to provide a hinge member which will be capable of being used with a pin having integral projections at its ends so as to 15 avoid the use of the common wire hinge pin and thus simplify the article itself and cheapen its construction and do away with the possibility of the end of the metallic pin catching in the hair; also to provide an 20 improved and simplified blank for the production of the hinge members for the purpose of decreasing the cost thereof. Further objects and advantages of the invention 25 will appear hereinafter.

Reference is to be had to the accompanying drawings in which—

Figure 1 is a rear elevation of a barrette showing a preferred form of this invention applied thereto;

Fig. 2 is an edge view of the same;

Fig. 3 is a sectional view on the line 3—3 of Fig. 2;

Fig. 4 is a sectional view on the line 4—4 of Fig. 1;

Fig. 5 is a bottom plan view of the hinge member before attachment to the barrette with the pin in position; and

Fig. 6 is a plan of a blank from which a plurality of these hinge members can be 40 made.

The invention is shown as applied to a barrette B of conventional form having a pin P and a hinge member H. This pin is different from the ordinary pins because 45 it has a pair of pivot lugs p integrally formed thereon in the pressing operation by which it is adapted to be pivotally mounted on the barrette.

The hinge member is preferably made 50 from a block, such as shown in Fig. 6, which shows a blank of celluloid having a series of longitudinal slots 10 extending all the way through it and twice as many transverse slots 11 extending from one surface 55 nearly to the opposite surface and equally spaced from the ends of the longitudinal

slots. These transverse slots extend through to one side but not to the other, while the longitudinal slots extend all the way through and across the transverse slots centrally. 60 The block, having been made in this form, is cut up into pieces along the dot-and-dash lines shown in the figure, and each one of these pieces constitutes a hinge member H. The grooves or slots 10 and 11 are unmodified in the hinge member except that each one of the longitudinal slots 10 is bisected in cutting the block up, and the surface shown in Fig. 6 is the one that is cemented 65 to the surface of the barrette. 70

The cementing operation is performed after the pin P is placed in position from the back and moved inwardly until the pivot lugs p come to the ends of the short transverse slots 11. The surface through which 75 the pin was moved is cemented to the back of the barrette and it is found in practice that the cement runs down into the grooves 11 sufficiently to prevent reciprocation of the pin in these slots 11 for any material distance, but the pin is prevented from sticking because there is such a leverage that it 80 can be turned easily even after the cement has hardened or it can be moved while it is hardening to prevent sticking. 85

Although the pin sticks out from the hinge member through the edge of the slot 10 that is cut in cutting up the blank it is impossible to remove the pin from the hinge member after the latter is once cemented 90 in position. This groove or slot 10 is extended clear through the outer edge of the hinge member so that there will be perfect freedom for manipulation of the pin up to a position at right angles to the back of the 95 barrette. In this way a neat construction is secured which is all celluloid, no metal being required. This is an important improvement because the placing of the metal pins has always been a time-consuming operation, 100 being performed entirely by hand, whereas now the introduction of the pin is even easier than it was before and the placing of the metal pivot pin is entirely eliminated. The doing away with the projection of the 105 pins from the hinge member is also an important feature because they have been likely to catch in the hair and form an unfinished construction which detracts from the appearance of the article. 110

Although I have illustrated and described only one form of the invention and shown

it as applied to a conventional barrette, I am well aware of the fact that the invention can be carried out in other forms and can be applied to other hair ornaments than 5 the one shown. Therefore, I do not wish to be limited in these respects, but what I do claim is:—

1. As an article of manufacture, a barrette having a hinge member cemented to the 10 surface of the barrette and having a cross-shaped groove therein extending from said cemented surface, the transverse portion of said groove stopping short of the opposite surface, and the longitudinal portion extending through it, and a pin having a lug on each side fitting in the transverse portion of said groove, the cement which unites the block to the barrette extending into said groove to prevent reciprocation of the pin 20 therein.

2. As an article of manufacture, a hinge member of the character described consisting of a solid block having a transverse groove extending normally from its supporting surface, and a longitudinal groove crossing said transverse groove for receiving a hinge pin, the stock entirely closing the rear end of the longitudinal groove. 25

3. As an article of manufacture, a hinge 30 member of the character described having a transverse groove extending normally from its supporting surface nearly to the

opposite surface, and a longitudinal groove crossing said transverse groove and extending from one surface to the other for receiving a hinge pin. 35

4. As an article of manufacture, a blank for a series of hinge members consisting of a strip of celluloid or the like having a plurality of longitudinal slots extending entirely therethrough, and two transverse slots located across each longitudinal slot at equal distances from its ends and extending from one side of the blank nearly to the other side, whereby when said blank is cut up 40 into pieces by cutting through between two slots and also cutting through the center of each longitudinal slot, twice as many blanks will be produced as there are longitudinal slots. 45

5. As an article of manufacture, a blank for a series of hinge members consisting of a strip of celluloid or the like having a plurality of slots extending entirely therethrough, and slots located across each slot 50 and extending from one side of the blank nearly to the other side, whereby when said blank is cut up into pieces blanks will be produced having cross-shaped grooves for receiving the pivot ends of barrette pins. 55

In testimony whereof I have hereunto affixed my signature.

EDWARD E. HAMILTON.
